(57) CLAIM

The ornamental design for a vehicle upper grille, as shown and described.

DESCRIPTION

FIG. 1 is a front perspective view of an vehicle upper grille showing our new design;

FIG. 2 is a front view thereof;

FIG. 3 is a rear view thereof;

FIG. 4 is a top view thereof;

FIG. 5 is a bottom view thereof; and,

FIG. 6 is a side view thereof.

It will be understood that the broken lines shown in the drawings illustrate portions of the vehicle upper grille that form no part of the claimed design.
